UNITED STATES PATENT OFFICE.

HENRY A. HERR, OF CHICAGO, ILLINOIS, ASSIGNEE TO ACME ELECTROTYPE COMPANY,
OF CHICAGO, ILLINOIS, A CORPORATION OF ILLINOIS.

WORKHOLDER FOR CUTTING OR DRESSING MACHINES.

Application filed April 1, 1922. Serial No. 543,574.

To all whom it may concern:

Be it known that I, HENRY A. HERR, a citizen of the United States, residing at Chicago, in the county of Cook and State of Illinois, have invented certain new and useful Improvements in Workholders for Cutting or Dressing Machines, of which the following is a specification.

This invention relates to improvements in plate holding means particularly adapted though not necessarily limited in its use for holding electrotype plates during the dressing down and planing or smoothing operation.

15 In the manufacture of printing plates and especially electrotypes, the back of the plate when the plate is first formed, is rough and uneven and in order to finish the plate it is necessary to dress or plane down the back.

20 This is a very particular operation and must be done with accuracy so that the plate will set or fit correctly. The dressing down has heretofore been done first on what is known as a roughing machine which planes 25 off the back but leaves the surface rough, after which the plate is placed in a planing or smoothing machine for the finishing operation.

These machines embody a reciprocating 30 knife or cutter and co-operating with the cutter, in proximity thereto, one or more steel or iron rollers have been employed, and which rollers are of a length to extend entirely across the plate and rest upon the 35 back thereof and roll with respect to the back during the cutting of the plate. Pressure is exerted upon the rollers so as to force or hold the plate firmly against the bed of the machine.

40 Inasmuch as these rollers are of metal, the bodies thereof do not yield, with the result that in the event that the plate is provided with a high portion, the roller will be tilted or raised by such high portion which causes 45 the roller to move out of engagement with other portions of the plate, and as the cutting proceeds, the plate will not be held firmly, with the result that the plate will slip or move causing considerable damage or 50 injury to the plate and often times under these conditions the plate will be trimmed or planed to an uneven thickness, which is not desirable.

With this construction or type of machine 55 it has heretofore been impossible to operate

upon two plates at the same time which are of uneven thicknesses, as the thicker plate will hold the roller or rollers elevated above the thinner plate and the latter will not be held at all by the rollers.

To overcome these difficulties and objections and to provide an improved roller attachment for machines of this character, the body portion or work engaging surface of which roller is adapted to yield to compensate the irregularities of the surface of the plate to be operated upon, whereby the roller will under all conditions exert its pressure upon the back of the plate throughout the entire length or width of the plate, is one of the objects of the present invention.

A further object is to provide an improved roller of this character by means of the use of which two or more plates of unequal thicknesses may be simultaneously dressed or planed, and each of the plates will be firmly gripped or forced against the bed of the machine by the same roller or rollers.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention and in which—

Figure 1 is a perspective view of a portion of a shaving or dressing machine having a roller constructed in accordance with the principles of this invention applied thereto.

Figure 2 is a detail vertical sectional view taken on line 2—2, Figure 1.

Figure 3 is an enlarged detail view in vertical section showing the roller in position.

While this improved roller attachment will be described and claimed in connection with the dressing or smoothing of the back of electrotypes, it is to be understood that the same can be used with equal efficiency in the preparing of other forms of printing plates and therefore it is to be understood that this invention is not to be considered as being limited in its use with electrotypes.

Referring more particularly to the drawing the numeral 10 designates a supporting bed having a shoulder or stop 11 at the for-

ward end thereof and against which stop one edge of the plate or work 12 engages when the latter rests upon the bed 10.

Mounted to reciprocate upon the machine 5 is a cutter head 13, having connected therewith a cutter 14, the head with the cutter mounted thereupon is adapted to be reciprocated by means of suitable racks 15.

All of these parts are of the ordinary and 10 well known construction, common in machines of this character.

Arranged in advance of the cutter 14 is a pressure roller 16, the body portion of which may be constructed of any suitable material 15 preferably metal. This roller 16 is provided with a face or coating 17 formed of suitable yieldable material such as rubber or composition which is of a suitable consistency or 20 hardness to force or clamp the work 12 firmly upon the bed 10 but is yieldable to a sufficient extent so that the surface of the roller when engaging a high portion or projection 18 on the back of the plate will yield and the remaining portion of the roller will 25 remain in contact with the surface or back of the work 12. That is to say, the surface of the roller 12 is constructed of a material adapted to yield so that the roller will compensate the irregularities of the back or 30 surface of the plate to be operated upon, and at the same time the roller will hold the entire adjacent portion of the plate or work firmly against the bed 10.

Pressure may be exerted upon the roller 35 10 so as to force the same against the work 12, in any desired or suitable manner, in the present illustration however, a spring 19 is shown encased within a housing 20, carried by the head 13, the normal tendency of the 40 spring 19 being to force the roller against the plate. A cam 21 is provided for raising the roller against the stress of the spring 19, when desired, and this cam 21 may be of any suitable construction and provided with 45 a handle 22, for operating the same.

With this improved construction it will be manifest that the work will not only be firmly held against the bed but the surface of the roller will yield for any irregularities 50 without moving other portions of the roller out of contact with the surface of the work, with the result that the work or plate 12 will be firmly held flat against the bed 10.

Obviously many changes may be made in the construction of the roller and the mounting thereof together with the controlling means therefor, within the scope of the claims, without departing from the spirit of this invention, and the roller may be applied with equal efficiency to any form of 55 dressing or finishing machine of this character to co-operate with the bed for holding the plate, and any number of rollers may be employed.

What is claimed as new is:—

1. In combination, an electrotype supporting bed, a cutter bodily movable over the bed, and means adapted to engage and rest upon the electrotype for holding the same firmly upon the bed, the said means being 70 rotatable and bodily movable over the electrotype in advance of the cutter and having a yieldable work engaging surface.

2. In combination, an electrotype supporting bed, a cutter, said cutter being movable 75 over the bed, said cutter and bed being relatively movable one with relation to the other, an electrotype holder movable with and with respect to the cutter and adapted to engage and rest upon the surface of the electrotype 80 in proximity to the plane of operation of the cutter upon the electrotype, and means for exerting pressure upon the said holder for holding the electrotype firmly upon the bed, the said electrotype holder embodying a 85 yieldable work engaging surface to compensate the irregularities of the surface to be operated upon.

3. In combination, an electrotype supporting bed, a cutter, said cutter and bed being movable over the work, said cutter and bed being relatively movable, one with relation to the other, a holding roller movable with the cutter and with respect thereto and adapted to engage and rest upon the electrotype adjacent the plane of operation of the cutter thereupon, and means for causing the roller to exert pressure upon the electrotype, the electrotype engaging surface of the roller being yieldable to compensate the 100 irregularities of the surface of the electrotype.

In testimony whereof I have signed my name to this specification on this 30th day of March, A. D. 1922.

H. A. HERR.
